CLAIM

We claim the ornamental design for a bed end, as shown and described.

DESCRIPTION

FIG. 1 is a front perspective view of a bed end of the new design;

FIG. 2 is a right side elevational view of the bed end of FIG. 1;

FIG. 3 is a front elevational view of the bed end of FIG. 1; FIG. 4 is a left side elevational view of the bed end of FIG. 1; FIG. 5 is a rear elevational view of the bed end of FIG. 1; FIG. 6 is a top plan view of the bed end of FIG. 1; and, FIG. 7 is a bottom plan view of the bed end of FIG. 1.

The portions of the Figures shown in broken lines are for illustrative purpose only and form no part of the claimed design.
